(75) Inventor: **Lionel Wodecki**, Maisons Alfort (FR)

Primary Examiner — Anhdao Doan
(74) Attorney, Agent, or Firm — Ziolkowski Patent Solutions Group, SC

(73) Assignee: **General Electric Company**, Schenectady, NY (US)

(57) **CLAIM**
The ornamental design for a pediatric magnetic resonance scanner, as shown and described.

(**) Term: **14 Years**

(21) Appl. No.: **29/379,679**

(22) Filed: **Nov. 23, 2010**

DESCRIPTION

(51) **LOC (9) Cl.** **24-01**
(52) **U.S. Cl.** **D24/159**
